UNITED STATES PATENT OFFICE.

JOHN S. SHANKS, OF CANTON, OHIO.

COMBINED DRIER AND LAUNDRY-STOVE.

1,272,721.

Specification of Letters Patent.

Patented July 16, 1918.

Application filed March 31, 1915, Serial No. 18,330. Renewed February 11, 1918. Serial No. 216,650.

To all whom it may concern:

- Be it known that I, JOHN S. SHANKS, a citizen of the United States, residing at Canton, in the county of Stark and State of Ohio, have invented certain new and useful Improvements in Combined Driers and Laundry-Stoves, of which the following is a specification, reference being had therein to the accompanying drawing.
- 10 My invention relates to improvements in combined driers and laundry stoves.
- The object of my invention is to provide a device of this character in which the ordinary laundry stove is used to heat the drier 15 and at the same time providing means whereby the laundry stove is not necessarily heated when not in use for laundry purposes, but is used solely for the purpose of heating the drier.
- 20 A further object of my invention is to so arrange a burner that the top of the laundry stove will not be heated, yet providing for the proper amount of heat for the drier, as hereinafter more fully described.
- 25 A still further object of my invention is to provide a drier of this character in which a greater circulation of air through the drier is obtained and can be readily regulated for regulating the temperature of the 30 drier and having certain details of structure and operation hereinafter more fully set forth.

In the accompanying drawings—

- Figure 1 is a perspective view of the drier, 35 partly broken away, showing the interior of the stove and the heat conveying tubes.
- Fig. 2 is a side elevation of my improved device, partly in section.
- Fig. 3 is a vertical sectional view taken on the line 3—3, of Fig. 2.
- 40 Fig. 4 is a vertical sectional view taken on the line 4—4, of Fig. 2.
- Fig. 5 is a horizontal sectional view taken on the line 5—5, of Fig. 2.
- 45 Fig. 6 is an enlarged perspective view of the shield plate showing the relative position of the drier heating burner.

In combined driers and laundry stoves, the heat utilized for heating the stove has 50 also been used for heating the drier, while in my device, separate burners are used for heating the driers. By this arrangement, it will be seen that when it is not desired to

use the stove for heating the irons, the stove is not unnecessarily heated and, therefore, 55 has a great advantage over those in which the one set of burners is used for heating the stove and also the drier. By my improved arrangement of the burners, it will be seen that when the stove is being used to 60 heat the irons, there is more or less heat passing to the drier, but when the burners for heating the driers are in use, there is practically no heat in the stove and, therefore, 65 the room in which the drier is placed is not unnecessarily heated, as is the case with the ordinary drier now in use.

Referring now to the drawings, 1 represents the body portion of my improved drier, which is preferably of a rectangular 70 shape and of any desired size. My improved drier is preferably for use in small and large apartment houses, institutions and residences where there is no way in which to dry clothes.

75 The body portion 1 is provided adjacent its upper end with the sliding rack frames 2, which form closures for the end of the body-portion and serve as a means whereby the clothes may be readily placed in the 80 drier and removed therefrom by sliding the racks therein. Below these racks is arranged the screen 3, which prevents any of the clothes that may drop from the racks falling upon the heating flues arranged below and 85 which will be hereinafter more fully described.

90 Arranged in front of the body-portion 1, is the laundry stove 4, which is of a rectangular form and preferably made of sheet metal or cast iron and of a width about equal to one-third of that of the body-portion of the drier, as fully shown in Fig. 4 of the drawings. This stove can, if desired, 95 be made of the coal type and I have shown a grate 5 adjacent its lower end, but I preferably use gas as fuel for the said stove. Within the upper end of the stove are arranged the stove heating burners 6, which are adapted to heat the top 7 of the stove 100 for the purpose of ironing or boiling the clothes. In rear of these burners are the drier heating burners 8, which will be hereinafter more fully described. Communicating with the lower end of the stove 4 is a narrow flat 105 flue 9, which extends the entire width of

the stove and having its lower end communicating with the lower end of the drier, as fully shown in Fig. 2 of the drawing. The flue 9 is provided with a damper 11, by 5 means of which the circulation of heated air through the drier may be regulated, which will be presently described.

Communicating with the upper end of the stove 4 and forming a part thereof and adjacent its ends, are the passages 7' and 8', which communicate with the heating flues 9 and 10, which extend within the lower portion of the body-portion 1 below the screen 3. The opposite ends of the heating 10 flues 9 and 10 communicate with the vertical passage 11, arranged in the rear portion of the stove. Said passage 11 communicates with the opening 12, which in turn is in communication with the pipe 13, 15 which leads upwardly and allows the products of combustion to pass from the heating flues to the chimney or otherwise from the room in which the drier is arranged.

Arranged at the ends of the burners 8, 20 are the obliquely extending shield plates 14, which extend downwardly through the passages 7' and 8' and enter the ends of the heating flues 9 and 10. These shield plates are preferably made of semi-circular form 25 having their lower sides open, which allows the proper amount of air to pass to the burner and to the flues 9 and 10 and yet prevent the heat from the burners engaging the top of the stove and heating the 30 same. The flues 9 and 10 are U-shaped in form and preferably rectangular in cross section, although they could be round or any other shape and extend across the body of the drier to a point close to the rear wall, 35 as fully shown in Fig. 5 of the drawing. These flues are supported by legs 15 and 16 carried by the bottom 17 of the drier, or on the floor if a bottom pan is not provided.

Arranged below the flues 9 and 10 are 40 correspondingly shaped air flues 18 and 19, which have their outer ends communicating with the connections 20, which have their outer ends in communication with the space 21, in the rear of the stove 4. The ends of 45 the connections 20 are closed by a damper 22, pivoted at 23, whereby the amount of fresh air allowed to pass into the flues 18 and 19 may be regulated. While I have shown a pivoted damper for controlling the 50 amount of air supplied to these flues, it will be understood that a sliding damper could be used. The upper ends of the flues 18 and 19 are provided with openings 24 for discharging the fresh air to the drier. Below the fresh 55 air flues 18 and 19 and above the bottom 17 of the drier is a horizontally arranged plate 25 having its rear end extending upwardly at 26, and spaced from the rear wall 28 of the drier. This plate is of a width slightly 60 less than that of the drier so as to allow

heavy air, containing moisture, to pass downwardly below the plate 25 with the space 29, as is clearly shown in Fig. 2 of the drawing and is supported by the collars 27 carried by the supporting legs 14 and 15.

70

Communicating with the flue 9, through the opening 10, are horizontally arranged flues 30, which extend across the bottom of the drier within the space 29 and provided with openings 31. The heavy air, containing moisture, passes from the spaces 29 through the opening 31 to the flues 30 and out through the passage 9 to the fire-box of the stove 4.

75

The burners 6 and 8, as shown in Fig. 5, 80 are supplied with the proper mixture of air and gas through the pipe 33 to cause a perfect combustion of gas and this pipe 33 is supplied with gas by means of the pipe 34, all of which will be understood and needs 85 no further description. The burners 32 are special in shape and construction and are designed especially for the purpose intended—being supplied with the proper mixture of air through the air mixers 90 shown, and with the proper amount of gas by means of the gas valves shown and gas supply pipes 34, to cause a perfect combustion of gas, all of which will be understood and needs no further description.

95

When the heat is to be used for heating the irons or boiling the clothes, the burners 6 are lighted and the heated air from the stove passes downwardly through the passages 7' and 8' to one end of the flues 9 100 and 10. The heat continues to travel around through said flues and is discharged into the vertical flue 11, from which it passes upwardly into the pipe 13 and is discharged from the room at any desired point. This outward travel of the heated air causes the heavy moisture containing air within the spaces 29 of the drier to travel upwardly 105 through the openings 10 and to the flue 9 from whence it is conveyed to the stove 4. 110 The fresh supply of air passes through the connections 20 into the flues 18 and 19 and discharged through the opening into the body of the drier. The fresh air rises upwardly around the flues 9 and 10 through 115 the screen and is heated and comes in contact with the clothes on the racks 2 in the upper portion of the drier.

115

From the foregoing description it will be 120 seen that I have produced a drier of this character in which the same heat used in heating the top of the stove can be used by heating the drier and also providing means whereby the drier may be used without heating, to any extent, the stove and yet obtain 125 the proper amount of heat to properly dry the clothes within the drier.

125

While I have shown and described this specific manner of arranging the burners in order to accomplish this result, it will be un- 130

derstood that this could be varied without departing from my invention.

Having thus described my invention, what I claim and desire to secure by Letters Patent is:

1. The combination with a drier, of a laundry stove adjacent thereto and in communication with a drier at its upper and lower ends, a series of burners within the 10 stove for heating the top of a laundry stove and a series of burners for supplying the drier with the proper amount of hot air.

2. The combination with a drier, of a laundry stove adjacent the drier, flues communicating with the upper end of the stove and the drier, burners within the stove adjacent the flues, steel plates above the burners and extending into the flues for conveying the heat to the flues, substantially as 20 shown and described.

3. The combination with a housing, means for removably supporting the clothes within the housing, of a laundry stove adjacent the housing, flues communicating with the upper 25 end of the stove and the housing, burners within the stove adjacent the flues, shield plates above the burners and extending downwardly into the flues for conveying the heat from the burners to the flues, and a flue 30 communicating with the lower end of the stove and the lower end of the housing.

4. The combination with a drier, removable racks for supporting the clothes within the drier, a laundry stove adjacent the drier, flues communicating with the upper end of the stove and the drier, burners adjacent the flues, shield plates above the burners and extending obliquely into the flues and adapted to convey the heat from the burners to the 35 flues, a flue communicating with the lower end of the stove and the lower end of the drier and means for supplying the drier with fresh air.

5. The combination with a drier and its 45 clothes supporting racks, a laundry stove adjacent the drier, flues communicating with the upper end of the stove and the drier, a series of burners in the stove for heating the top of the stove, a second series of burners within the stove and adapted to heat the drier and means whereby the heat from either series of burners is caused to travel through the flues to the drier.

6. The combination with a drier and its 55 clothes supporting racks, flues within the lower end of the drier and having their outer ends in communication with one side of the drier, a laundry stove adjacent the drier, passages communicating with the upper end of the stove and with the outside arm of the flues conveying the heat from the stove, and a vertical passage communicating with the inside arms of the flues for conveying the heat from the flues, a passage communicating with the lower end of the stove 60

and the lower end of the drier and means for supplying fresh air to the drier directly below the heating flues.

7. The combination with a drier and its clothes supporting racks, two heating flues 70 arranged in a horizontal alinement within the lower end of the drier and having their outer free ends communicating with one side of the drier, a laundry stove adjacent the drier and having two passages communicating with the outer free arms of the flues, a vertical passage communicating with the inner free arms of the flues for conveying the products of combustion from the flues, fresh air pipes directly below the heating flues 80 and communicating with the outside atmosphere for supplying fresh air to the drier directly below the flues and a passage communicating with the lower end of the drier and the laundry stove. 85

8. The combination with a drier and its clothes supporting racks, a screen extending across the drier above its lower end, two heating flues supported in horizontal alinement above the lower end of the drier, passages communicating with one end of each of the flues and with the stove, the opposite ends of the flues communicating with a discharge passage for conveying the products of combustion from the flues, fresh air supplying tubes directly below the flues within the drier and in communication with the outside atmosphere and having openings in their upper faces, a passage communicating with the lower end of the drier and the lower 90 end of the stove, a damper in said passage for regulating the passage of air from the drier to the stove, and a damper for regulating the supply of fresh air to the tubes. 95

9. The combination with a drier and its 105 clothes supporting racks, heating flues, arranged in horizontal alinement within the drier a suitable distance above its lower end, a laundry stove adjacent the drier, burners within the stove, passages communicating 110 with the stove and one end of the flues, a discharge passage communicating with the opposite ends of the heating flues, pipes within the lower end of the drier directly below the heating flues and having their outer 115 ends in communication with the outside atmosphere, a damper for controlling the supply of fresh air to the said tubes, a plate extending across the lower end of the drier below the fresh air tubes, and a passage communicating with the space below the plate and with the lower end of the laundry stove, substantially as shown and described. 120

10. The combination with a drier, a laundry stove adjacent the drier, obliquely arranged passages communicating with the upper end of the stove and with the heating flues within the drier, a series of burners within the upper end of the stove adjacent its front for heating the top of the stove, a 125 130

series of burners adjacent the rear end of the stove in an alinement with the obliquely arranged passages, semi-circular shield plates above the burner and extending obliquely within the passages whereby the heat from the burners is directed into the flues within the drier without unnecessarily heating the stove.

11. A drier comprising a housing, a heating flue within the housing, a chimney flue extending into the housing, a burner within the inlet end of the heating flue and the outlet end of the flue communicating with the chimney flue, whereby the chimney flue draft 10 draws and elongates the burner flame into the heating flue.

12. A drier comprising a housing, a stove in communication with the housing, a heating flue within the housing, the stove having 20 a chimney flue, a burner in the inlet end of the heating flue and the outlet end of the flue communicating with said stove chimney flue.

13. A drier comprising a housing, a stove in communication with the housing and having a chimney flue, two approximately U-shaped heating flues within the housing, burners in the inlet ends of the heating flues and their outlet ends in communication with said stove chimney flue. 25

14. A drier comprising a housing, a stove in communication with the housing and having a chimney flue, two approximately U-shaped heating flues within the housing, burners in the inlet ends of the heating flues and located at opposite sides of the said chimney flue and the outlet ends of the heating flues communicating with the said stove chimney flue. 30

In testimony whereof I hereunto affix my 40 signature in the presence of two witnesses.

JOHN S. SHANKS.
